CLAIM

The ornamental design for a vibratory plate compactor, as shown and described.

DESCRIPTION

FIG. 1 is a top, front, left-side isometric view of a vibratory plate compactor showing our new design;

FIG. 2 is a front elevation view thereof;

FIG. 3 is a top, front, isometric view thereof;

FIG. 4 is a left-side elevation view thereof;

FIG. 5 is a top, rear, right-side isometric view thereof;

FIG. 6 is a rear elevation view thereof;

FIG. 7 is top, rear, left-side isometric view thereof;

FIG. 8 is a top, left-side isometric view thereof;

FIG. 9 is a top plan view thereof; and,

FIG. 10 is a bottom plan view thereof.

The broken lines represent unclaimed portions of the design. All of the broken lines form no part of the claimed design.
